COMBINED SERVING TRAY AND TUMBLER

Clair O. Musser, 12997 Blairwood Drive,
Studio City, Calif. 91604

Filed Aug. 9, 1974, Ser. No. 496,044

Term of patent 7 years

Int. Cl. D7—99

U.S. Cl. D7—3

FIG. 3.

FIG. 4.

FIG. 6.

FIG. 7.

FIG. 1.

FIG. 2.

FIG. 1 is a top plan view of a combined serving tray and tumbler showing my new design;

FIG. 2 is a side elevational view thereof;

FIG. 3 is an isometric view thereof, the tumbler being omitted for convenience of illustration;

FIG. 4 is a top plan view of this tray;

FIG. 5 is a bottom plan view of this tray;

FIG. 6 is a side elevational view of this tray; and

FIG. 7 is an end elevational view of this tray.

I claim:

The ornamental design for a combined serving tray and tumbler, as shown and described.
